E. A. HAWTHORNE,
ILLUMINATING APPARATUS,
APPLICATION FILED FEB. 16, 1917.

1,356,144.

Patented Oct. 19, 1920.

Inventor:
Ellsworth A. Hawthorne.
by Harry Bowditch Kamm. Atty's.

UNITED STATES PATENT OFFICE.

ELLSWORTH A. HAWTHORNE, OF BRIDGEPORT, CONNECTICUT.

ILLUMINATING APPARATUS.

1,356,144.

Specification of Letters Patent. Patented Oct. 19, 1920.

Application filed February 16, 1917. Serial No. 149,087.

To all whom it may concern:

Be it known that I, ELLSWORTH A. HAWTHORNE, a citizen of the United States, and a resident of Bridgeport, in the county of 5 Fairfield and State of Connecticut, have invented an Improvement in Illuminating Apparatus, of which the following description, in connection with the accompanying drawings, is a specification, like characters on the 10 drawings representing like parts.

This invention relates to illuminating apparatus such, for example, as the lamps commonly used on vehicles and a primary purpose is to provide a device which will 15 be free from objectionable glare.

My invention will be best understood by reference to the following description of one illustrative embodiment thereof, taken 20 in connection with the accompanying drawing, wherein—

Figure 1 is a central vertical section through a lamp embodying my invention, and

Fig. 2 is a section on the line 2—2 of 25 Fig. 1.

My invention may be embodied in many forms and it is applicable to lamps of different styles and constructions. In the accompanying drawings I have shown one 30 style of lamp in which my invention may advantageously be used and for clearness I will describe specifically the lamp here shown.

Referring first to Fig. 1, the lamp illustrated 35 includes a suitable casing 3, having a light-transmitting opening 5, with a suitable closure therefor such as the glazing 7, and having an interior reflecting surface, conveniently in the form of a separate reflector 9, which is preferably a paraboloid of comparatively long focus to project forward in parallel beams rays of light falling thereon from a focally disposed source. Within the casing is a light 11, herein shown 40 as an incandescent bulb, disposed on the axial line of the reflector 7. This light may be mounted on an adjustable socket member 13, to permit the same to be moved in and out axially. The construction and operation 45 of the socket 13 may be the same as the socket shown in my application Serial #108062, filed July 7, 1916. It will be understood that if the socket 13 is adjusted so that the light 11 is at the focus of the paraboloid, the reflected rays will be projected forward in parallel beams and the lamp will

function as a true spot light; but, if the light is moved out of focus, a divergent cone of reflected rays will be produced.

In order to permit the use of a long focus 60 reflector without unduly increasing the size of the lamp, the light transmitting opening 5 is placed at the same distance from the reflector and a secondary reflector 15, in the form of a spherical zone may be provided, 65 the center of this zone herein being the focus of the parabola. The two reflectors 9 and 15 are connected by the frusto-conical portion 17. If the paraboloid were extended to the position of the reflector 15, the rays 70 would fall thereon at such an angle that they would be of comparatively little value. The spherical reflector will return certain of the rays to the light source and they will heat and materially increase the efficiency of 75 the nitrogen-filled incandescent lamp which I preferably use. At the same time, the glazing 7 is placed at a sufficient distance from the reflector to permit the addition of the glare-preventing devices which I shall 80 shortly describe and the size of the lamp is kept within reasonable limits.

To prevent the light emitted from the lamp from having an objectionable glare, I have here shown an opaque screen 19, in the 85 form of a tube or cylinder, disposed substantially coaxially with the reflector and carried by the glazing 7. I have here shown it as secured thereto by a screw 21 and cooperating nut 22. The cylinder extends inwardly and surrounds the lamp bulb 11, but is cut away at one side as shown at 23 to provide the integral segmental extension 25, laterally overlying the light at one side thereof and extending into close proximity 95 to the reflector 9.

The truly cylindrical portion of the screen 19 at the left of the cut-away portion 23 in Fig. 1, is preferably so proportioned as to intercept all the direct rays of light from 100 the source 11, which would otherwise pass through the opening 5 of the lamp casing. Thus the light emitted from the lamp consists solely of reflected rays and the intense and concentrated direct rays are eliminated, 105 thus doing away with much of the glare. The direct rays of light, of course, inevitably diverge and would be transmitted through the opening 5 in the form of a cone, independently of the form of the reflector and 110 the position of the lamp. The elimination of these rays, therefore, makes it possible to

control the direction in which the light is projected and the height of the beam from the light, as will hereinafter more fully appear.

5. The segmental extension 25 overlies the light at one side thereof and cuts off a portion of the reflector from its rays. A portion of the beam from the light is thus eliminated and, if the beam is projected as a 10 cone, a part is cut off and only the rays which extend in a certain direction are utilized. Consequently it is possible to provide a light which will not shine above a certain level, and which therefore, when 15 used on a vehicle, will not be projected into the eyes of pedestrians or drivers of other vehicles.

To permit the light source to be effectively screened at one side thereof and at 20 the same time to provide for such variations in the distance between the glazing and the reflector as may occur in different lamps, I may provide an adjustable tip portion 27, in the form of a segment mounted on the 25 integral segmental portion 25 in such manner that it may be adjusted longitudinally thereon. I have here shown the member 27 as provided with slots 29 and rivets 31 are passed through these slots and the portion 30 25 and set with sufficient tightness to hold the tip 27 in adjusted position while permitting it to be moved when it is desired to adjust it. By the provision of such a tip it is possible to provide a lamp with an 35 opaque screen extended at one side of the axial line from the casing 7 practically into contact with the reflector 9, as illustrated in Fig. 1.

While I have described in considerable 40 detail the illustrative embodiment of my invention shown in the accompanying drawings, I have done so in order that the structure and its operation might be more quickly comprehended and not because all the details referred to are essential. The mechanism employed might be widely varied without departing from the spirit of my invention and what I claim and desire to secure by Letters Patent is:—

50. 1. A lamp comprising a casing having an interior reflecting surface and a light transmitting opening, a closure for said opening, a substantially axially located light in said casing and a tubular member secured to said closure in front of said light and having an integral segmental portion laterally overlying the same.

60. 2. A lamp comprising a casing having an interior reflecting surface and a light transmitting opening, a closure for said opening, a lamp in said casing mounted for adjustment along the axial line of said reflector and a tubular member coaxially mounted on

said closure and having an integral segmental extension laterally overlying said 65 light.

3. A lamp comprising a casing having an interior reflecting surface and a light transmitting opening, a closure for said opening, a lamp in said casing located on the axial 70 line of the reflector, and a fixedly located opaque screen carried by said closure and at one side of said line extending from the closure into close proximity to the reflector, and having an axially adjustable terminal 75 portion adjacent the latter.

4. A lamp comprising a casing having an interior reflecting surface and a light transmitting opening, a closure for said opening, a substantially axially located light in said 80 casing and a tubular member secured to said closure in front of said light and having an integral segmental portion laterally overlying the same said segmental portion having an adjustable tip. 85

5. A lamp comprising a casing having an interior reflecting surface and a light transmitting opening, a closure for said opening, a substantially axially located light in said 90 casing, a tubular member mounted on said closure in front of said light and a segmental member mounted upon one side thereof by a pin and slot connection.

6. A lamp comprising a casing having an interior reflecting surface and a light transmitting opening, a closure for said opening, a substantially axially located light in said casing, a cylinder having a base secured to said closure and extending over said light and into close proximity to the reflector, 100 the cylinder being cut away at one side thereof adjacent the light permitting rays therefrom to fall on the reflector. 95

7. Illuminating means comprising a reflector, a light coöperating therewith and 105 screening means comprising a cylinder supported with a base in front of the light and its side extending inwardly about the light into close proximity to the reflector, said cylinder being cut away at one side adjacent 110 the light permitting rays therefrom to fall on the reflector and a segmental tip slidably mounted on the end of said wall.

8. A lamp comprising a casing having an interior reflecting surface and a light transmitting opening, a substantially axially located light in the casing, a screen in front of the light comprising a base secured to said closure and a flange or side wall extending therefrom over the light, said screen 115 being cut away on one side and a segmental extension slidably mounted on said wall. 120

In testimony whereof, I have signed my name to this specification.

ELLSWORTH A. HAWTHORNE.
